LAUNDRY HANDLING APPARATUS

Ralph B. Presher, Lafayette, Calif., assignor to Ambassador Business Corporation, doing business as Ambassador Laundry Company, Oakland, Calif., a corporation of California

Filed Nov. 23, 1964, Ser. No. 413,190
7 Claims. (Cl. 211—131)

This invention relates to apparatus for facilitating the handling of laundry in a highly expeditious manner.

In the operation of a commercial laundry, it is frequently necessary for workers to move articles of laundry from one place to another. For example, a worker may be required to remove articles of laundry, piece by piece, from a bin, or the like and place them into a machine such as an ironer. It is desirable that such a handling procedure be as efficient and rapid as possible in order to provide a high throughput of laundry.

It is therefore an object of the present invention to provide laundry handling apparatus for facilitating the movement of laundry from one place to another with a maximum of efficiency.

Another object of the invention is the provision of apparatus for enabling workers to handle laundry with a minimum expenditure of time and effort in the feeding of laundry into a machine, or the like.

Still another object of the invention is the provision of laundry handling apparatus wherein the top of a pile of laundry in a bin or the like is maintained at a constant level during depletion of the pile by workers removing laundry therefrom piece by piece, thus enabling the workers to unload the laundry with a maximum of efficiency.

It is a further object of the invention to provide laundry handling apparatus of the class described which includes a plurality of bins circumferentially arrayed upon a rotary frame such that laundry may be loaded into the bins at one station adjacent the frame and rotated to a second station for unloading from the bins, the level of the top of the laundry in the respective bins being at all times the same.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

FIGURE 1 is a side elevational view of the laundry handling apparatus of the present invention.

FIGURE 2 is a plan view of the apparatus.

FIGURE 3 is a sectional view taken at line 3—3 of FIGURE 2.

FIGURE 4 is a sectional view taken at line 4—4 of FIGURE 2.

FIGURE 5 is a cross sectional view through a rotary mounting of the support frame of the apparatus, illustrating particularly stop means for stopping the frame at predetermined rotary positions.

2

FIGURE 6 is a sectional view taken at line 6—6 of FIGURE 5.

Referring now to the drawing, the laundry handling apparatus of the present invention will be seen to include a support frame 11 journaled for rotation about a vertical axis upon a base 12. A plurality of bins 13 are carried by the frame at circumferentially spaced positions thereof. Such bins preferably open outwardly from the frame such that laundry may be readily stacked or piled in the bins and be readily removed therefrom. The laundry may thus be loaded into the bins from one station adjacent the apparatus and, upon rotation of the frame, be unloaded from the bins at another station displaced, for example, 90° about the rotary axis of the frame from the first station. It will be thus appreciated that laundry may be loaded into the bins and unloaded therefrom in a substantially continuous manner, empty bins being delivered to the loading station and loaded bins being delivered to the unloading station upon rotation of the frame.

In the unloading of the laundry piece by piece from the bins for feeding into an ironer, or for other purposes, maximum efficiency is attained when the repetitive unloading operation is each time accomplished under identical conditions. The operation then becomes second nature to the workers and is conducted in a substantially automatic fashion. In this regard, it is extremely important that the level of the top piece of laundry piled in the bins 13 is constant. Otherwise, workers in removing the top piece of laundry from a bin must continuously compensate for differences in level as the pile is depleted. The initial levels of laundry in bins delivered to the unloading station may also vary due to inconsistencies in the loading thereof. When the level is always the same, the unloading workers become accustomed to the level and automatically grasp the top piece of laundry without consideration and in the same manner each time. Accordingly, as an extremely important feature of the present invention, the bins 13 are carried upon the frame 11 in such a manner that the elevation or level of the bins varies inversely with the amount or height of laundry piled therein to thereby maintain the level of the top of the pile constant. In this regard, the bins 13 are preferably individually suspended from the frame by means of tension springs 14. The bins thus assume varied levels in inverse relation to the amount of laundry contained therein. When a bin is fully loaded, the springs yield to an extent determined by the weight of the load and the bin is depressed to a low level such as indicated in the phantom line position of FIGURE 1. As the laundry is unloaded from the bin piece by piece, the springs gradually urge the bin upwardly to thereby maintain the top of the pile at a constant level.

Considering now the laundry handling apparatus in greater detail as to the preferred structure thereof, it is to be noted that the frame 11 advantageously includes a central vertical shaft 16 from which peripheral frame members 17 radially project at 90° intervals. Each peripheral frame member includes a horizontal portion 18 radially secured to the shaft 16 adjacent its lower end. The horizontal portion terminates outwardly in a perpendicular vertical side portion 19 which at its upper end extends into an upwardly and inwardly inclined por-

tion 20 in turn secured to the shaft adjacent its upper end. Aligned pairs of frame members 17 may be respectively provided as integral diametric frame members if desired. Vertical struts 21 are secured between intermediate points of the horizontal and inclined portions 18 and 20 of the respective frame members 17, and a plurality of horizontal struts 22 are secured at vertically spaced positions between the vertical struts associated with circumferentially adjacent frame members. In addition horizontal struts 23 are radially secured between the vertical side portions 19 and vertical struts 21 in upwardly spaced relation to the horizontal portions 18 of the frame members.

To facilitate rotary mounting of the support frame 11 upon the base 12, the lower end of shaft 16 is preferably secured to a depending cup 24 having an outwardly flared annular flange 26 provided with a depending peripheral rim 27. The base 12 is provided with an upright shaft 28 having a support disc 29 coaxially secured in spaced relation to the free end thereof as shown in FIGURE 5. The free end of the shaft 28 is received in the cup 24 which rests upon the support disc 29. Thus, the cup, and support frame mounted thereon, are rotatable upon the shaft of the base.

Considering now the bins 13 carried upon the frame 11, it is to be noted that in the instant embodiment four bins are provided respectively between circumferentially adjacent frame members 17. Each bin includes a base 31 having an outer arcuate edge extending substantially 90°, equal length radial side edges 32, and an inner straight edge 33 extending between the side edges. Each bin further includes marginal walls 34 and 36 extending upwardly from the radial side edges 32 and straight edge 33 of the base 31. The bins are thus open at their fronts and tops, and moreover are of a configuration to fit into the spaces of the support frame respectively outlined by circumferentially adjacent peripheral frame members 17 and the associated struts 21, 22, 23.

With regard to the spring mounting of the bins 13 on the support frame 11, it is to be noted that pluralities of the springs 14 are preferably secured at their upper ends to the struts 23 of the frame and at their lower ends to the bins at positions along the radial side edges 32 of the bin bases 31, as best shown in FIGURES 2 and 3. The bins are thus resiliently suspended from the support frame. In order to limit movement of the bins to the vertical direction, vertical guide rods 37 are secured centrally between lowermost vertically spaced pairs of the horizontal struts 22, as best shown in FIGURES 2 and 4. Guide sleeves 38 secured to the exteriors of the walls 36 of the bins 13 are slidably disposed upon the guide rods 37. Additional vertical guidance is facilitated by vertical guide rods 39 respectively secured to the struts 23 and horizontal portions 18 of the frame members 17 with the lower end portions of the guide rods depending from the latter and provided with stop heads 41 at their free ends. Apertured ears 42 projecting from the radial edges of the bases of the bins are slidable upon the depending lower end portions of the guide rods 39. Thus, three point vertical guidance of each bin 13 is provided in the resilient suspension thereof. When the bins are loaded with laundry, they are urged downwardly against the loading of the springs 14, the bins being stopped by the heads 41 of the guide rods 39 when loaded to capacity. The level of the bins thus depends upon the amount of laundry or height of the pile loaded therein, the higher the pile, the lower the level of the bin. As a result, the levels of the tops of the piles of laundry in the respective bins are all at the same level regardless of differences in the heights of the piles, and such constant level is maintained during unloading, the bins rising as the piles are depleted.

It is desirable that the support frame 11 be stopped at predetermined angular positions of its rotation in order that the bins 13 be readily positioned adjacent, for example, loading and unloading stations. Accordingly,

stop means are preferably provided to this end to stop the frame at angular intervals, in the illustrated embodiment intervals of 90°. More particularly, as shown in FIGURES 5 and 6 rollers 43 are preferably mounted upon the shaft 28 at diametrically opposed positions and loaded, as by means of springs 44 in the radially outward direction into resilient engagement with the inner peripheral wall of rim 27.

The rim is provided with pairs of spaced fillets 46 at 90° intervals, each pair of fillets defining a groove 47 therebetween engageable by the rollers 43. Consequently, as the frame is rotated, the rollers roll upon the rim 26, and at 90° intervals encounter the fillets. The rollers are then depressed slightly against the loading of the springs 44 in passing over a fillet and upon reaching a groove 47 are urged outwardly into engagement therewith to thus stop the frame.

What is claimed is:

1. Laundry handling apparatus comprising a support frame, means mounting said frame for rotation about a vertical axis, a plurality of bins adapted to hold laundry, and means mounting said bins upon said frame at circumferentially spaced positions thereof for restored vertical movement to levels in inverse relation to the height of piles of laundry in said bins.

2. Laundry handling apparatus according to claim 1, further defined by said bin mounting means comprising spring means secured to said frame and said bins for resiliently urging said bins upwardly.

3. Laundry handling apparatus according to claim 1, further defined by stop means for stopping rotation of said frame at predetermined angular positions of its rotation.

4. Laundry handling apparatus comprising a base, a support frame mounted upon said base for rotation about a vertical axis, said frame having openings therein at circumferentially spaced intervals, a plurality of laundry bins respectively disposed in said openings of said frame, and tension spring means suspending said bins from said frame.

5. Laundry handling apparatus according to claim 4, further defined by guide means carried by said frame and associated with said bins to restrict movement thereof to the vertical direction.

6. Laundry handling apparatus comprising a vertical shaft, a plurality of peripheral frame members projecting radially from said shaft at 90° intervals, each of said frame members including a horizontal portion radially secured to said shaft adjacent its lower end and terminating outwardly in a vertical side portion extending at its upper end into an upwardly and inwardly inclined portion secured to said shaft adjacent its upper end, vertical struts secured between intermediate points of said horizontal and inclined portions of said frame members, a first plurality of horizontal struts secured at vertically spaced positions between adjacent ones of said vertical struts, a second plurality of horizontal struts radially secured between said vertical struts and said vertical side portions of said frame members in upwardly spaced relation to the horizontal portions thereof, a base, means mounting said shaft upon said base for rotation about a vertical axis, a plurality of bins, said bins each including a base having an outer arcuate edge extending substantially 90° and equal length radial side edges interconnected by a straight inner edge, said bins each including marginal walls extending upwardly from said radial side edges and inner edge of said base of the bin, said bins respectively disposed between circumferentially adjacent ones of said frame members, pluralities of tension springs secured at one end to said second horizontal struts and at their other end to said bins at positions along the radial side edges of the bases thereof, first guide rods secured vertically to said first horizontal struts, guide sleeves secured to said bins and slidably disposed on said guide rods, second guide rods vertically secured to said second horizontal struts and horizontal portions of said frame members and depending from the latter, and apertured

ears projecting from said bins adjacent the radial side edges of the bases thereof and slidably engaging the depending portions of said second guide rods.

7. Laundry handling apparatus according to claim 6, further defined by said means mounting said shaft upon said base comprising a cup depending from said shaft and having an outwardly flared annular flange with a peripheral rim depending therefrom, a second shaft projecting upwardly from said base, a support disc coaxially secured in spaced relation to the free end of said second shaft, said free end of said second shaft received in said cup, at least one roller mounted on said second shaft and spring loaded radially outward into engagement with said rim,

and a plurality of pairs of spaced fillets secured to said rim and respectively defining grooves therebetween at 90° intervals, said roller engageable with said grooves.
